UNITED STATES PATENT OFFICE

ARTHUR T. FOSTER, OF BEVERLY, MASSACHUSETTS, ASSIGNOR TO UNITED SHOE MACHINERY CORPORATION, OF PATERSON, NEW JERSEY, A CORPORATION OF NEW JERSEY

MANUFACTURE OF TURN SHOES

Application filed October 17, 1929. Serial No. 400,399.

This invention relates to the manufacture of turn shoes. In the manufacture of shoes of that kind it is customary to use tacks as temporary fastening means for holding the upper in lasted relation to the sole at the toe and along the sides of the forepart and shank. It is very important that these tacks be driven in such manner as not to penetrate entirely through the sole, since tack holes 5 are likely to result in stains visible on the outer face of the sole of the finished shoe. Such stains are especially objectionable in turn shoes in view of the fact that shoes of that type are largely dress shoes for women's 10 wear and must, therefore, present a fine appearance. This consideration has imposed heretofore a substantial limitation upon the use of machinery for lasting turn shoes, especially as far as the side-lasting operation 15 is concerned. For lasting the toes there is commonly used a combined pulling-over and toe-lasting machine so constructed as to afford substantial insurance against penetration of the lasting tacks entirely through the sole; but the sides of the shoes along the 20 forepart and the shank have been heretofore usually lasted by hand because of the difficulty, in the use of side-lasting machines of the well known "hand method" type, of controlling the depth of penetration of the 25 lasting tacks into the work with sufficient precision for purposes of turn shoe work. When the tacks are driven by hand, moreover, it is very difficult, even with the exercise of great care, to avoid occasional penetration of a tack through the sole with the 30 objectionable results above mentioned.

In view of the above and other considerations, the present invention, in one important aspect, provides an improvement in methods of making turn shoes, especially in respect to the manner of fastening the upper to the sole in the lasting operation. Turn shoe soles are customarily provided each with an inside channel lip, that is, a lip formed by an incision or channel directed outwardly toward the edge of the sole to receive the upper-attaching seam; and in accordance with the 35 novel method of this invention, in one aspect, portions of the upper are fastened to this 40 lip over the bottom of the last in the lasting operation to hold the upper in lasted position. More particularly, as herein illustrated, the upper is pulled successively in different locations to subject it to lasting strain, 45 and while it is held under strain in each location a metallic fastening is inserted through the upper and the inside channel lip and clinched to fasten the upper initially yet permanently to this lip which, by reason of its 50 relation to the body of the sole, is well adapted to withstand the strain of the upper thereon and thus to hold the upper securely in lasted position. The fastenings preferably utilized are fine wire staples, which are unobjectionable as permanent parts of the shoe 55 and also involve no danger of damage if hit accidentally by the needle of the sewing machine in the later operation of sewing the upper to the sole, the staples being, moreover, so located that they are substantially out of the line of the upper-attaching seam. Not only, therefore, is all danger of objectionable 60 results due to penetration of lasting fastenings through the sole entirely eliminated, but advantages also arise from the fact that the work is in a condition especially convenient and satisfactory for the sewing operation. Additional reasons for this condition 65 are that the upper is held more securely by the clinched staples than by lasting tacks driven only into the sole, and that because of the absence of any danger of objectionable 70 results from interference between the sewing needle and the lasting fastenings, it is practicable to insert the staples at shorter intervals than lasting tacks, especially along the 75 sides of the shoe, so that the upper is held more closely adjacent to the edge of the sole 80 for the operation of the sewing machine. Furthermore, the novel method is well adapted to be carried out by the use of staple-lasting machines of a type now largely used in the manufacture of welt shoes, with important 85 advantages in respect to economy and to the character of the results in the lasting of the shoes, the characteristic features of a machine of that type being illustrated and described in Letters Patent No. 1,796,451, 90 95 100

granted on March 17, 1931, upon an application of George Goddu.

The invention is herein illustrated by reference to operations such as above described 5 performed only along the sides of the shoe at the rear of the toe end, since it is regarded as preferable to use for lasting the toe a combined pulling-over and toe-lasting machine such as commonly used for that purpose, that 10 machine being so constructed, as above explained, as to avoid any substantial danger of penetration of the lasting tacks through the sole. It is to be understood, however, that the invention is not limited in its applicability to the lasting of the sides of the shoe. 15

In addition to its method aspects, the invention further provides an improvement in turn shoes. It will be recognized that the lasting fastenings connecting the upper to 20 the inside channel lip of the sole and permanently incorporated in the shoe increase the security with which the upper is fastened to the sole; and since they are inserted, as illustrated, in locations where the upper is 25 subjected to pulling strain in the lasting of the shoe, they are especially effective in maintaining the upper in the condition required for the best results in the completed shoe.

20 The invention will now be more particularly described by reference to the accompanying drawing and thereafter pointed out in the claims.

In the drawing,

25 Fig. 1 is a perspective view of a turn shoe lasted along the sides of its forepart and shank in accordance with this invention;

Fig. 2 is a view illustrating the step of 30 fastening the upper to the inside channel lip of the sole in the side-lasting operation;

Fig. 3 is a view partly in perspective and partly in cross-section showing the shoe after it has been lasted and sewed, with the upper 35 trimmed at one side only;

Fig. 4 is a cross-section at the toe of the shoe in a location indicated by the line IV—IV of Fig. 1, illustrating the positions of the toe-lasting tacks, and

Fig. 5 is a cross-sectional view of the shoe 40 at the rear of the toe after the shoe has been turned.

As illustrated in the drawing, the materials of the turn shoe comprise a sole 10 and an upper consisting of the usual upper leather 45 12 and lining 14. These shoe materials are assembled on the last wrong side out, that is, with the outer face of the sole next to the last and with the lining outside of the upper. After the assembling of the materials on the 50 last the lasting operation is preferably performed first at the toe end portion of the shoe, especially if the toe is lasted, as it commonly is and as herein contemplated, by a combined pulling-over and toe-lasting machine of the type illustrated in Letters Pat-

ent No. 1,280,613, granted on October 1, 1918, upon an application of Orrell Ashton. Machines of that type have means for driving a plurality of lasting tacks *t* for holding the upper in lasted position around the toe, 70 and as hereinbefore suggested are so constructed that these tacks are driven without any substantial danger of penetrating entirely through the sole. The relation of such toe-lasting tacks to the shoe materials is illustrated in Figs. 1 and 4. 75

After the lasting of the toe the side-lasting operation is performed along the forepart and the shank, the shoe herein shown being one of the "nailed-seat" type which is not 80 lasted at the heel end until after the shoe has been turned. It will be observed that the sole 10 is provided, on that face which is outermost as the sole is positioned on the first last, with an inside channel lip 16 formed by an incision or channel directed outwardly toward the edge of the sole to receive the seam 18 (Fig. 3) whereby the forepart and shank portions of the upper are secured to the sole after the lasting of the toe and sides 85 of the shoe. For purposes of this invention, in accordance with the procedure illustrated, the upper is secured to this inside channel lip in the lasting of the sides of the forepart and shank portions of the shoe by lasting 90 fastenings comprising fine wire staples *s* which are driven through the upper and the lip and are clinched on the lip.

While the invention is not dependent upon the use of machinery for lasting the sides 100 of the shoe, the novel method is herein illustrated as carried out by the use of a machine of the type disclosed in the above-mentioned Letters Patent No. 1,796,451. In the use of such a machine the shoe is presented by the 105 operator in engagement with a work rest 20 (Fig. 2) which enters the inside channel of the sole and supports the lip 16, and while the shoe is thus positioned the upper is pulled heightwise of the last and inwardly over the 110 sole by a gripper 22 and is then pressed inwardly against the outer face of the lip 16 by a staple-guiding nozzle 24 which moves toward the shoe in a direction inclined to the outer face of the sole. After the upper has 115 thus been pressed against the lip in a position opposite the work rest 20, the staple *s* is driven through the upper and the lip in a location farther inwardly over the sole 120 than the edge of the last bottom by a driver 26 and is clinched by the work rest which serves as an anvil. The staple is thus driven in a direction inclined downwardly toward the sole and the bottom face of the last, so that its legs are clinched in comparatively 125 close relation to the base of the lip. It will be understood that these lasting operations are performed successively in different locations along the sides of the shoe, the shoe being moved by the operator to present it in 130

the different positions for side-lasting. It will thus be seen that, for the purposes in view, the upper is subjected successively in different locations along the sides of the shoe 5 to lasting strain heightwise of the last and inwardly over the sole by the pull of the gripper 22, and that while it is held under lasting strain in each location by the nozzle member 24 it is fastened initially, yet permanently, to the inside channel lip 16 of the sole by a staple which is driven through the upper and the lip in the location where the upper is subjected to strain and is clinched on the lip.

15 After the shoe has been lasted at the toe and the sides, the upper, as herein illustrated, is further secured to the sole by the thread seam 18. In the shoe herein shown the sole has also an outer channel to provide a 20 shoulder 28 against which the upper is sewed, although the invention is not limited to the use of a shouldered sole. After the sewing, the margin of the upper is trimmed, as illustrated at the left hand side of Fig. 3, 25 the lasting tacks at the toe also being removed. The last is then withdrawn from the shoe and the shoe is turned and mounted on the second last, after which the heel end of the shoe is lasted in the customary manner 30 and the remaining manufacturing operations are performed. Fig. 5 illustrates the condition of the shoe after it has been turned and before it has been mounted on the second last. It will be understood that in operations 35 performed on the second last the lip 16 and the margin of the upper are pressed closer to the body of the sole than indicated in this figure, and also that in the completed shoe the inner face of the sole and the lip and 40 adjacent margin of the upper are covered by the usual sock lining.

From the foregoing description it will be evident that the method of this invention serves to eliminate danger of objectionable 45 results due to penetration of lasting fastenings through the sole, especially along the sides of the shoe where under prevailing manufacturing conditions such danger is more commonly encountered; and that in 50 addition it gives rise to other important advantages in the preparation of the shoe for the operation of the sewing machine. The staples are conveniently and preferably driven in locations where they are substantially out of the line of the upper-attaching seam, and even if one of the fine wire 55 staples is hit by the needle of the sewing machine, there is no substantial danger of blunting the point of the needle or of other 60 damage. It is therefore practicable to space the staples at shorter intervals along the sides of the shoe than has been customary in the use of side-lasting tacks, so that the upper 65 is held more closely adjacent to the edge of the sole than heretofore for the operation of

the sewing machine, especially along the inwardly curved shank. Moreover, the upper is held more securely by the clinched staples than by lasting tacks driven only into the sole, and the inside channel lip being well 70 adapted to withstand the strain of the upper thereon, it is accordingly practicable to subject the upper to greater strain in side-lasting than when lasting tacks are used. The further fact that the novel method is well 75 adapted to be carried out by the use of machinery affords opportunity for important economies as well as improved results in lasting.

It will also be recognized that the shoe 80 produced by this novel method is of improved quality by reason of the fact that the lasting staples connecting the upper to the inside channel lip of the sole in locations along and closely adjacent to the upper-attaching seam serve as reinforcements increasing the security with which the upper is fastened to the sole, these staples contributing further to the production of a well made shoe because of the fact that they are 85 the actual lasting fastenings inserted at the time of the lasting operation in locations where the upper was subjected to the lasting strain. The staples, moreover, by reason of their relation to the sole, present no projections or ridges on the inside of the shoe such as might be perceptible in the wear of the shoe. This will be evident especially by reference to Fig. 5, where it will be seen that after the shoe has been turned the legs of the 90 staples are inclined at only very small angles to the inner face or "plane" of the sole, the cross-bars lying substantially parallel to that face. It will be understood that by the leveling pressure thereafter applied to the sole in the usual course of manufacture the staples are pressed still more nearly parallel to the plane of the sole. The legs and cross-bar of each staple accordingly lie in a plane approximately parallel to the bottom of the wearer's 95 foot.

Having described the invention, what I claim as new and desire to secure by Letters Patent of the United States is:

1. That improvement in methods of making turn shoes which consists in assembling on a last shoe materials comprising an upper and a sole having an inside channel lip with the shoe materials wrong side out, subjecting 115 portions of the upper to lasting strain and while holding them under strain securing them initially yet permanently to said lip by inserting fastenings through the upper and the lip in locations over the bottom of the last, 120 and thereafter removing the last and turning the shoe.

2. That improvement in methods of making turn shoes which consists in assembling on a last shoe materials comprising an upper 130

and a sole having an inside channel lip with the shoe materials wrong side out, subjecting portions of the upper to lasting strain and heightwise of the last and inwardly over the 5 bottom of the last while holding them under strain fastening them initially yet permanently to said lip by inserting staples through the upper and the lip and clinching the staples, and thereafter removing the last and 10 turning the shoe.

3. That improvement in methods of making turn shoes which consists in assembling on a last shoe materials, comprising an upper and a sole channeled to provide an upper-at- 15 taching shoulder and also having an inside channel lip, with the shoe materials wrong side out, lasting portions of the shoe by pulling the upper successively in different locations and securing it in each location where 20 the pull is applied, before pulling it in the next succeeding location, by inserting a fastening through the upper and said lip, and thereafter fastening the upper to said shoulder, removing the last and turning the shoe.

25 4. That improvement in methods of making turn shoes which consists in assembling on a last shoe materials comprising an upper and a sole having an inside channel lip with the shoe materials wrong side out, lasting 30 portions of the shoe by pulling the upper successively in different locations and fastening it in each location where the pull is applied, before pulling it in the next succeeding location, by inserting a staple through the upper 35 and said lip in a direction inclined toward the bottom of the last and clinching the staple, and thereafter sewing the upper to the sole, removing the last and turning the shoe.

5. That improvement in methods of making 40 turn shoes which consists in assembling on a last shoe materials comprising an upper and a sole having an inside channel lip with the shoe materials wrong side out, lasting the sides of the forepart and shank portions 45 of the shoe progressively by pulling the upper successively in different locations and fastening it in each location where the pull is applied, before pulling it in the next succeeding location, by inserting a metallic fastening 50 through the upper and said lip in a location farther inwardly over the sole than the edge of the last bottom and clinching the fastening, and thereafter sewing the forepart and shank portions of the upper to the sole by a 55 seam located substantially out of the line of the row of metallic fastenings, removing the last and turning the shoe.

6. That improvement in methods of making 60 turn shoes which consists in assembling on a last shoe materials, comprising an upper and a sole having an upper-attaching shoulder and a lip located farther inwardly from the edge of the sole than said shoulder, with the shoe materials wrong side out, lasting 65 the sides of the shoe by pulling the upper suc-

cessively in different locations and fastening it in each location where the pull is applied, before pulling it in the next succeeding location, by inserting a staple through the upper and said lip and clinching the staple, and thereafter sewing the upper to the shoulder of the sole, removing the last and turning the shoe. 70

7. A turn shoe having a sole provided with an inside channel lip and having its upper secured to the sole by a thread seam and additionally along said seam by lasting staples of fine wire extending through the upper and said lip in locations where the upper was subjected to pulling strain in the lasting of the 80 shoe, the cross-bars of the staples engaging the upper inside of the shoe in substantially parallel relation to the inner face of the sole and the legs of the staples being inclined at such small angles to said face that the legs 85 and cross-bar of each staple lie in a plane approximately parallel to the bottom of the wearer's foot.

8. A turn shoe having a sole provided with an upper-attaching shoulder and with a lip 90 located farther inwardly from the edge of the sole than said shoulder and having its upper secured to the shoulder of the sole by a thread seam and also secured to said lip by lasting staples inserted in locations where 95 the upper was subjected to pulling strain in the lasting of the shoe.

In testimony whereof I have signed my name to this specification.
